(57) **CLAIM**

The ornamental design for a bottle, as shown and described.

DESCRIPTION

FIG. 1 is a front, right, isometric view of a bottle showing our new design;

FIG. 2 is a rear, right isometric view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines immediately adjacent to the shaded areas in the figure drawings define the bounds of the claimed design and form no part thereof; all other broken lines in the drawings depict portions of the article that form no part of the claimed design.
